UNITED STATES PATENT OFFICE.

ANDREW B. OLSON, OF KANSAS CITY, MISSOURI.

APPARATUS FOR PICKING UP PINS, &c.

SPECIFICATION forming part of Letters Patent No. 531,384, dated December 25, 1894.

Application filed June 6, 1893. Serial No. 478,781. (No model.)

To all whom it may concern:

Be it known that I, ANDREW B. OLSON, a citizen of the United States, residing at Kansas City, in the county of Jackson and State 5 of Missouri, have invented certain new and useful Improvements in Apparatus for Picking Up Pins, &c.; and I do hereby declare that the following is a full, clear, and exact description thereof, such as will enable others to make and use the same, reference being had to the accompanying drawings, forming a part of this specification.

The primary object of my invention is to enable a quantity of pins, tacks, &c., to be taken from any place or receptacle in which they are either found conglomerate or scattered and self arranged, and held in position, so as to be readily and conveniently seized by the hand and applied to use; and it consists, in the novel construction and combination of parts such as will first be fully described and specifically pointed out in the claims.

In the drawings: Figure 1, is a view in perspective of my improved apparatus for picking up pins, with the lower portion of the receiver broken away to show the mode of attachment of the guiding standard and bowed spring plate thereto. Fig. 2, is a view of the holder disconnected from the pin receptacle, 25 and attached to a table or similar device. Fig. 3, is a detail view of the magnetized pin carrier.

Similar letters of reference indicate corresponding parts in all the figures.

Referring to the drawings, A represents a 35 bowl or receiver, which is made preferably from metal or glass, so as not to be easily upset and of a suitable depth to contain pins, tacks or other like utilities in considerable quantity and open at the top. In the under side portion of the bottom of the receiver A, is made a groove a, which extends in a horizontal direction from one side of said receiver in the direction of the other side, and a short 40 distance beyond the centerpoint, between said sides. In the under side of said receiver A, and in the groove a, at a point equi-distant from the sides of said receiver is made in an upward direction a screw threaded perforation b, in which is fitted a screw B.

C represents the guiding standard, which

consists of a single piece of wire, one end c, of which is extended beneath the receiver A, in the slot a, and between the inner side of said slot and the head of screw B. The other 55 end of the said wire is bent at right angles and extended in a vertical direction close in position to the outer side of said receiver, and to a point a considerable distance above the upper horizontal edge of said receiver, 60 and is then bent at right angles to form the stop c', and extended in a vertical direction near the side of said receiver; thence said wire is bent in a downward direction to the slot a, and thence extended along said slot 65 to a position on the other side of the screw B, opposite the end c' of said wire, and between the side of said slot a, and the head of said screw.

The retracting holder arm D consists of a 70 flat bowed or curved spring plate of considerable length and narrow in width. In one end of the curved arm d, is made a perforation d', which end is inserted in the slot a of the receiver A, and beneath the ends c, c' of the guiding standard C. Through the perforation d', in the end of the plate D is inserted the screw B, which also secures the ends c, c' of the standard C, within the slot a, of the receiver. The other end of the plate D, is bent 75 upward and extended forward between the sides of the guiding standard C, and upon said end is attached the pin or tack carrier and holder E. Said holder consists of a single piece of magnetized iron bent in the shape of 80 a horseshoe—the parallel outer ends of which piece of iron are made to terminate in sharp points as at e, e. Over the curved portion of the holder E, is looped a flat plate or clasp e'. Through the sides of clasp e' is made in a 85 vertical direction the perforation e'. The clasp e' is slightly wider than the opening between the sides of the guiding standard C, and said clasp is placed upon the upper side and outer end of the spring plate D, which is 90 extended between said guiding standards in which end of said plate is made a perforation d'. Through the perforation e' of clasp e' and the perforation d' of the spring plate D, is inserted the screw F. Upon the under side of 95 the plate D and to said screw is fitted a nut f'. In Fig. 2, the spring plate pin holder and

guide are shown detached from the receiver, and secured by a single screw b' to the top of a table in which position the guiding standard C, and the spring plate D is permitted to swivel upon a common pivot. To connect the lower portion of the guide C with the spring plate D, lugs c^1 , c^2 are formed upon both outer edges of the plate D, and bent over the horizontal ends c , c' of the standard C.

10 In the operation of the improved apparatus for picking up pins, &c., the receiver A is supplied with pins or tacks in the desired quantity. Pressure is applied to the thumbscrew F by the hand and the ends e , e' of the holder E forced downward within the receiver. The magnetic attraction of the holder E, which acts as a distributing agent, causes a large number of the pins or tacks which adhere upon, and dispose themselves in various positions on the parallel portions of the magnet. As soon as the pressure is relieved from the thumb screw F, the spring plate D causes the holder E to retract, the guide C, controlling the movements laterally of the said spring plate D, and the clasp e' is brought against the stop c^x on the guide C, and its movements arrested. In this position of the holder the pins, tacks, needles, &c., which ordinarily are difficult to pick up singly by the hand are presented in convenient positions so as to be readily seized by the hand, and even when the points are presented the pins or tacks are supported by the carrier, while their positions are changed and thus prevented from puncturing the fingers.

35 It will be observed that as the pins are used in large quantities, many are spilled upon the table, and the length and elasticity of the arm D is utilized so as to extend the holder 40 any required distance; the standard C being extended a proportionate length.

I do not confine myself to the action of magnetism to pick up or elevate the articles which may be placed in the receiver, which necessarily is limited to all metallic substances, subject to the inductive energy of the magnet. Matches, toothpicks and similar articles of convenience may be picked up and held for use, the ends e , e' of the holder E,

being pointed and sufficiently sharp to enter the material. I am thus enabled to select in less time than is usual from any quantity the most commonly used articles in factories, and large establishments requiring an expeditious supply of pins or tacks and in upholstering establishments, saving a large percentage of time and annoyance.

Having fully described my invention, what I now claim as new, and desire to secure by Letters Patent, is—

1. In an apparatus for picking up pins &c. the combination of a receiver for the pins &c. having guiding standards a bowed spring plate having its lower end supported by and connected with said receiver and its upper end extended between said standards and provided with pick up devices, and means for retaining said upper end within the said standards as and for the purpose described.

2. In an apparatus for picking up pins &c. the combination with the receiver for the pins &c. of a bowed spring plate having the lower end of said plate supported by and connected with said receiver standards mounted upon said end of said plate having a connection between their upper ends adapted to retain the upper end of said bowed spring plate and pick up devices upon said end and an operating handle substantially as shown and described.

3. In an apparatus for picking up pins &c. the combination with the receiver for the pins &c. having guiding standards attached thereto and a connection between their upper ends of a bowed spring plate having one end connected with the bottom of said receiver and the other end extended between the said standards and adapted to be drawn within and retract from said receiver and a magnet connected with said end of said spring plate and an operating handle connected with said spring plate adjacent to said magnet as and for the purpose described.

ANDREW B. OLSON.
